Patented Jan. 4, 1927.

UNITED STATES PATENT OFFICE.

RAYMOND B. RICHARDSON, OF CAPE CHARLES, VIRGINIA.

WHEEL GUARD FOR RAILWAY CARS.

Application filed June 11, 1926. Serial No. 115,261.

This invention relates to an improvement in wheel guards for railway cars and has for its primary object to provide a guard construction that may be readily associated with 5 railway cars now in use, for protecting the railway workmen from being caught beneath the wheels of the cars, which is a danger always present when the wheels are not provided with guarding devices.

10 The invention further aims to provide a guard that will positively prevent the accidental insertion of the hands or feet between the car wheels and track rails for thus overcoming any liability of a workman becoming injured.

15 Other objects will become apparent as the nature of the invention is better understood, the same comprising the novel form, combination, and arrangement of parts herein-20 after more fully described, shown in the accompanying drawing and claimed.

In the drawing wherein like reference characters indicate corresponding parts throughout the several views:

25 Figure 1 is a fragmentary side elevation of a railway car equipped with my novel wheel guard.

Figure 2 is a longitudinal section taken substantially upon the line 2-2 of Figure 1 and looking downwardly in the direction of the arrows, and

30 Figure 3 is an end elevation of the wheel guard when associated with the railway car.

Now having particular reference to the 35 drawing the car is indicated fragmentarily by the reference character A, while the wheels of the usual truck at one side of the car are designated B-B. In carrying out my invention, I provide a pair of relatively 40 elongated hinge knuckles 5-5 that are bolted or otherwise suitably secured to the under side of the car in predetermined longitudinal relation and outwardly of the truck wheels B-B as disclosed in Figure 1. Hing-45 edly secured to these knuckles 5-5 is an outer side guard plate 6 of metal or other suitable rigid material, said plate being formed at its upper edge with spaced knuckles 7, for registry with the knuckles 5-5 upon 50 the car to all of which is arranged a pivot bar 8. This guard plate 6 is of such a length as to extend somewhat beyond the wheels B-B of the truck and at its lower edge slightly beneath the tread of the rail C.

At the opposite ends of the outer side 55 guard plate 6 I provide end guards 9-9 at direct right angles to the guard plate 6 as clearly disclosed in Figure 2. These end guard plates are constructed of three sections as shown in Figure 3, the upper ends 60 of which are constructed for complementary association with hinge knuckles 10 arranged upon the under side of the car A outwardly of the truck wheels B-B so as to permit the pivotal mounting of the end plates upon the 65 under side of the car.

The center sections of the end guards terminate slightly above the tread of the rail C while the outer sections extend slightly therebeneath to a point flush with the lower 70 edge of the side guard plate 6.

The outer sections of the end guards are connected at their inner sides by one or more cross bars 10 that also serve as a means for limiting the inner swinging movement of the 75 center sections, and the consequent engagement of the same with the truck wheels B-B.

The opposite vertical edges of the outer 80 guard plate 6 are flanged inwardly as at 6'-6' in order that the end guards may be rigidly bolted thereto for preventing the swinging of the same upon their pivots. However, access may be had to the wheels so as to permit a skate to be positioned there-85 under and also to permit of the proper gag- ing of the wheels without necessitating the entire raising of the end panel.

A suitable latching means 13 is provided 90 between the center section of the end guards and one of the stationary sections to prevent the accidental outward swinging of the central sections when the car is traveling over the track way.

The outer guard plate 6 is formed at pre-95 determined points thereon with openings 14-14 to permit the usual truck journal boxes to extend therethrough while preferably, though not necessarily, said side guard plate is formed throughout its length with 100 openings 15 for purpose of lightness.

It will thus be seen that I have provided 105 a highly novel, simple, and efficient wheel guard construction for railway cars that is well adapted for all the purposes heretofore designated, and even though I have herein shown and described the same as consisting of certain detail structural elements, it is

nevertheless to be understood that minor changes may be made without affecting the spirit and scope of the appended claims.

Having thus described the invention, what I claim is:—

1. In a wheel guard for railway cars, a plate hingedly secured at its upper edge to the under side of the car outwardly of the truck wheels, and extending below said 10 wheels, said plate being formed with openings to permit the truck journal boxes to project through the plates, and guard plates hingedly secured to the under side of the car body at the opposite ends of said side 15 plates and at right angles thereto.
2. In a wheel guard for railway cars, a plate hingedly secured at its upper edge to the under side of the car outwardly of the truck wheels, and extending below said 20 wheels, said plate being formed with openings to permit the truck journal boxes to project through the plates, guard plates hingedly secured to the under side of the car body at the opposite ends of said side 25 plates and at right angles thereto, the opposite vertical edges of said side plate being flanged inwardly to permit of the attachment of the end guard plates thereto.

3. In a wheel guard for railway cars, a plate hingedly secured at its upper edge to the under side of the car outwardly of the truck wheels, and extending below said 30 wheels, said plate being formed with openings to permit the truck journal boxes to project through the plates, guard plates 35 hingedly secured to the under side of the car body at the opposite ends of said side plates and at right angles thereto, said end guard plates consisting of a central and a pair of side sections, said side sections being interconnected in back of the central section, and a latch arrangement between one of the side 40 sections and the central section.

4. In a wheel guard for railway cars, a plate hingedly secured at its upper edge to the under side of the car outwardly of the truck wheels, and extending below said 45 wheels, and end guard plates hingedly secured at their upper ends to the under side of the car body at opposite ends of said side 50 guard plates, said end guard plates being rigidly connected to the opposite ends of said side guard plates.

In testimony whereof I affix my signature.

RAYMOND B. RICHARDSON.
